UNITED STATES PATENT OFFICE.

GUSTAF A. SAFSTROM, OF CHICAGO, ILLINOIS.

INTERNAL-COMBUSTION-ENGINE EQUIPMENT.

Application filed November 20, 1922. Serial No. 602,005.

To all whom it may concern:

Be it known that I, GUSTAF A. SAFSTROM, a citizen of the United States, residing at Chicago, in the county of Cook and State of Illinois, have invented a new and useful Improvement in Internal-Combustion-Engine Equipments, of which the following is a specification.

My invention relates to attachments to the 10 motors of automobiles and, more particularly, to the well-known Ford engine.

One of my objects is to provide a timer device which may be substituted for the timer device supplied as a part of the equipment 15 of a Ford engine by which the contact elements of the timer device may be located at a point sufficiently remote from the operating parts of the engine that they will remain relatively free of oil and dirt and be 20 readily accessible for purposes of adjustment, repair and cleansing.

Another object is to provide a rigid and economical construction of so-called extension timer device.

25 Another object is to provide for the ready and accurate adjustment of the rotary contact member for the purpose of accurately timing the spark relative to the position of the pistons from which position provision is made for advancing the spark.

30 Another object is to provide an arrangement of mechanism for advancing and retarding the spark, which will not require the necessity of boring any additional holes 35 in the motor.

Another object is to provide as an attachment for the motor an improved form of extension filler tube by the use of which the lubricating oil in the crank-case, in the 40 "breathing" of the motor will not be forced through the apertured cap of the filler tube.

Another object is to provide an improved construction of filler tube which will permit the extension timer to be secured in a position 45 on the motor wherein the head of the timer is located closely adjacent to and above the filler tube, without unduly obstructing free access to the tube for the purpose of charging lubricating oil into the crank-case.

50 Another object is to provide an extension timer so positioned that it will not interfere with the adjusting of the fan-belt-adjusting screw of the motor and with which the current-conducting wires commonly provided as

a part of the motor installation may be used 55 without change.

Referring to the accompanying drawings:

Figure 1 is a view in front elevation of the well-known Ford motor, showing it as equipped with my improvements. Figure 2 60 is a view in sectional elevation of the extension timer, showing the cam-shaft of the engine in section. Figure 3 is a view in vertical sectional elevation of the extension filler tube employed. Figure 4 is a section 65 taken at the line 4-4 on Fig. 3 and viewed in the direction of the arrow; and Figure 5, an enlarged section taken at the line 5-5 on Fig. 1 and viewed in the direction of the arrows.

70 Referring to Figs. 1 and 2 of the drawings, the extension timer device therein shown comprises a housing member 5 of general cup shape and of such dimensions as to permit it to be substituted for the 75 regular Ford timer casing positioned on the end plate 6 of the engine and located at the end of the cam-shaft 7 thereof which is equipped with the gear 8. The Ford motor referred to is provided with a spring arm 80 9 pivoted to the engine casing at 10 and bearing against the end of the timer casing, the arm 9, in the substitution of my casing 5 for the timer casing formed as a part of the Ford equipment, operating to hold the timer 85 casing 5 in place, it being preferred that a clamping arm, represented at 11, and supplementing the arm 9, be provided. The arm 11, which is of spring metal, is shown as pivotally connected at 12 with the end 90 wall 6 of the motor casing and operates under its spring tension to exert at its outer, free end clamping force against the casing 5, pressing the latter to its seat. In the particular arrangement shown the outer, free, 95 ends of the arms 9 and 10 are arranged in overlapped position at the central portion of the casing 5.

The casing 5 contains an opening 13, tangentially disposed to the axis of the casing 100 in which opening the lower end of a tube 14 extends and is rigidly secured, against rotation therein, by means of a set-screw 15. The upper end of the tube 14 extends into, and is rigidly secured in, the stationary 105 base-section 16 of the head of the timer, these parts being connected together through the medium of the set-screw 17. The other,

top, section of the casing of the timer is represented at 18, this section being of general cup shape and telescoping at its lower, open, end with the base section 16, as shown, and adapted for rotation upon the said base section, the section 18 being shown as held against accidental displacement on the section 16, by means of a spring arm 19 pivotally connected, as by means of a screw 20, with an extension 21 of the base section 16, a spacer tube 22 being shown as surrounding the pivot 20 and interposed between the spring arm 19 and the extension 21. The outer, free, end of the arm 21 is provided with a projection 23 which seats in a depression 24 in the top of the casing section 18, this arm, while holding the section 18 on the base section 16, permitting the former to be rotated relative to the latter. The stationary contacts of the timer, which may be of a construction commonly employed, are located within, and carried by, the casing section 18 to be adjustable therewith about the axis of the casing.

The rotary contact of the timer which, in the operation of the latter, is caused to move, in succession, into engagement with the stationary contacts referred to, this rotatable contact being represented at 25 and being shown as in the form of a roller, is carried on the upper end of a shaft 26, the roller 25 being shown as journaled on a pin 27 mounted at its ends in spaced-apart ears 28 projecting laterally from a sleeve 29 surrounding the upper end of the shaft and confined thereon between a flange 30 on this shaft and a nut 31 screwed on the latter, with a washer 32 interposed between the nut and sleeve. The shaft 26 is located within the tube 14 and is rotatable therein, its lower end being journaled in a bearing 33 carried by the casing 5, this bearing being spaced from the wall of the casing containing the opening 13. The shaft 26 is provided below the tube 13 and above the bearing 33 with a worm gear 34 rigidly secured thereon and meshing with the gear 8 on the cam-shaft 7 whereby the rotatable contact 25 is driven from the shaft 7 through the medium of the gears 8 and 34, and shaft 26. Below the gear 34 the shaft 26 is provided with a collar 35 which aids in holding the shaft 26 against longitudinal movement.

The extension timer is applied to the casing of the engine, with the clamping arms 9 and 11 engaging the casing 5, to extend in the position shown in Fig. 1, in which position the timer structure is supported at its upper end on the extension of the filler tube hereinafter described.

Means, operable by the driver of the car, are provided for advancing and retarding the spark, these means, in accordance with the particular structure shown, comprising a link 36 pivoted at a deflected end 37 there-

of in a bearing clip 38 secured to the casing section 18 at one side of the axis thereof, the opposite end of this link being pivotally connected at 37' with the end of one arm 38' of a bell-crank lever 39, the other arm 40 of which is pivotally connected at 41 with the upper end of a link 42 which would be connected at its lower end with the crank-portion of the shaft of the timer-setting mechanism as commonly provided on the Ford automobile. The bell-crank 39 is shown as pivoted at its angle by a pivoting screw 43 which is provided to take the place of one of the screws commonly provided as a part of the Ford motor for holding the water connection 44 in place on the motor casing. The pivoting screw 43, shown in detail in Fig. 5, is provided with a threaded portion 45 at which it extends through the aperture in the flange of the connection 44 and screws into the casing of the motor as shown. The end of the screw beyond the connection 44 is of such form, as represented at 46, as to adapt the screw to be screwed into place by the application of a wrench thereto. The screw 45 beyond the portion 46 is in the form of a stud 47 which extends through the angle of the lever 40 at which portion the screw forms a journal support for this lever, the lever 40 being held on said stud against accidental disengagement therefrom by a cotter pin 100 located in a crosswise-extending aperture in the outer end of the stud, a washer 101 being interposed between the lever 40 and the cotter pin 100.

Referring now to the filler tube extension, the filler tube provided as a part of the standard equipment of the motor is represented at 48, the upper end of this tube being commonly provided with a breather cap. My extension filler tube is provided for assembly with a filler tube 48 at the upper inlet end of the latter, the breather cap referred to having been removed, this extension filler tube, shown in Figs. 1, 3 and 4, in accordance with the particular illustrated construction thereof, being formed, as by casting it from metal, or otherwise forming it, as desired, to provide a substantially vertically disposed portion 49 from which the tubular depending portion 50, of slightly reduced diameter depends, the portion 50 being of springy metal and containing upwardly-extending slots 51, as in the case of the breather cap commonly employed, and adapting the extension filler tube to be applied to position on the filler tube 48 by telescoping with the latter the part 50. The extension filler tube also is formed of an upwardly-extending tubular portion 52 located to one side of the portion 49 and in communication with the latter through the intermediate, crosswise-extending tubular portion 53, it being intended that the upper, open, end of the portion 52 be equipped with a breather

- cap 52^a of any suitable construction, as, for example, that shown and which is of a construction commonly provided as the standard equipment of a Ford motor. It is preferred that the upper end of the portion 52 be of such size and shape as to receive the particular breather cap provided as a part of the motor and to which the motor filler extension tube is applied so that 10 the breather cap supplied with the motor to which the extension filler tube is applied, may be used at the inlet end of the extension filler tube. It will be noted that the extension filler tube thus presents a wall, represented at 54, which extends into the path of the oil which is forced upwardly and out of the filler tube 48 in the breathing of the engine, and thus operates to cause the oil to precipitate in the extension filler tube and 20 flow back into the crank-case, with the manifest advantage of avoiding discharge of the oil through the breather cap at the top of the filler tube extension.
- The extension timer device applied to the 25 motor in the position as shown and described, extends into such a position that unless an extension filler tube providing for the oil filling opening, to one side of the filler tube 48, is provided, the extension timing device 30 would render difficult, if not impossible, the charging of the crank-case with oil. By employing my extension filler tube, which is preferably assembled with the filler tube 48 to a position in which the portion 53 of the 35 extension filler tube extends rearwardly, the inlet of the extension filler tube is caused to extend to one side of the extension timer, preferably rearwardly thereof, as shown, and in such position that oil may be readily 40 poured into the crank-case without disturbing the position of the extension timer and without danger of pouring oil on the latter.
- In accordance with the particular construction shown, it is desired that the extension filler tube serve as a support for the upper end portion of the extension timer, which latter rests at the portion thereof between the casing 5 and the section 18, upon the extension filler tube in crosswise-extending 45 position, it being preferred that the portion of the extension filler tube which is contacted by the extension timer, as stated, be formed with a recess 55, presenting an inclined bottom wall 56 which extends generally parallel 50 with the portion of the extension timer directly opposed thereto, it being understood that this recess is provided on the exterior of the extension filler tube.
- It will be understood from the foregoing 55 that by causing the extension timer device to extend to the left of the cam-shaft 7, the extension timer may be provided of relatively short length and the head of the timer may be so disposed, as shown, that the head 60 of the timer and the parts therein will be readily accessible for repair, adjustment and cleansing, and will extend in such position that it will be practically free of accumulations of oil and dirt thereon from the engine.
- Furthermore, the arrangement of the extension timer, as stated, renders the structure very rigid and stable.
- The construction and arrangement of the mechanism by which the section 18 of the timer head carrying the stationary contacts may be adjusted relative to the contact carried by the shaft 26, for advancing and retarding the spark, is a highly desirable arrangement not only because such adjustment 70 may be readily effected and this mechanism operate positively, but because it may be supported without requiring the boring of additional holes in the Ford motor as commonly provided, it being necessary only that one of the screws commonly provided for holding the connection 44 in place be replaced by the pivoting screw 43.
- The feature of mounting the contact 75 25 on the shaft 26 in a manner to permit this contact to be adjusted into different positions about the axis of this shaft, as stated, is of advantage as it permits of the accurate timing of the spark relative to the position of the pistons, from which position provision is made for advancing the spark, by a readily-performed operation, as compared with the operation required to be performed in the use of other constructions of timing devices.
- Another advantage of providing the extension timer as stated is that the current-conducting wires as provided in the regular Ford equipment may be attached to the binding posts of the timer extension.
- It will furthermore be stated that the extension timer as provided is so positioned as to avoid interference with the adjusting of the fan-belt-adjusting screw of the motor 100 represented at 102.
- While I have illustrated and described a certain construction embodying the features of my invention, I do not wish to be understood as intending to limit it thereto, as the same may be variously modified and altered without departing from the spirit of my invention, and in this connection it may be stated that while I have described the extension timer, with its operating mechanism and the extension filler tube as applied to 105 a motor of the type stated, as furnished to the public, it will be readily understood that, if desired, these parts may be provided initially with the motor, as distinguished from providing them as substitutes for other 110 parts in original installations.
- What I claim as new, and desire to secure by Letters Patent, is:
1. In combination with a motor of the Ford type, an extension timer applied to 115

the casing of the motor at the outer end of the cam-shaft thereof, the contacts of said extension timer relative to which the rotary contact thereof moves being adjustable about said rotary contact, and means for adjusting said first-referred-to contacts comprising a lever fulcrumed on a pivot device secured in the openings in the motor casing and in one side of the flange of the water-connection as provided in the motor and substituted for the securing device located in said openings.

2. In combination with a motor of the Ford type, an extension timer applied to the casing of the motor at the outer end of the cam-shaft thereof and extending upwardly in a direction away from the crank-shaft of the motor toward the oil filler tube, the contacts of said extension timer relative to which the rotary contact thereof moves being adjustable about said rotary contact, and means for adjusting said first-referred-to contacts comprising a lever fulcrumed on a pivot device secured in the openings in the motor casing and in one side of the flange of the water-connection as provided in the motor and substituted for the securing device located in said openings.

3. In combination with a motor of the Ford type, an extension timer applied to the casing of the motor at the outer end of the cam-shaft thereof and formed of a supporting part comprising parts rigidly connected together against relative rotation and a head having a portion at the upper extremity of the extension timer carrying the stationary contacts thereof and rotatably supported at a point closely adjacent the upper extremity of the device, and means for adjusting said stationary contacts comprising a lever fulcrumed on a pivot device secured in the openings in the motor casing and in one side of the flange of the water-connection as provided in the motor and substituted for the securing device located in said openings.

4. In combination with a motor of the Ford type, an extension timer applied to the casing of the motor at the outer end of the cam-shaft thereof, the contacts of said extension timer relative to which the rotary contact moves being adjustable about said rotary contact, and means for adjusting said stationary contacts comprising a bell-crank-lever fulcrumed on a pivot device secured in the openings in the motor casing and in one side of the flange of the water-connection as provided in the motor and substituted for the securing device located in said openings, and links pivotally connected with the arms of said bell-crank.

5. In combination with a motor of the Ford type, an extension timer adapted to be applied to the casing of the motor at the place occupied by the timer on the motor and as a substitute therefor, and an extension oil filler tube on the oil filler tube of the motor, said extension tube having upwardly-extending hollow portions connected at ends thereof by a hollow portion disposed crosswise thereof, said extension tube containing a recess in its upper surface, and said extension timer extending into the recess in said tube.

6. In combination with a motor of the Ford type, an extension timer adapted to be applied to the casing of the motor at the place occupied by the timer on the motor and as a substitute therefor, and an extension oil filler tube on the oil filler tube of the motor, said extension tube having upwardly-extending hollow portions connected at ends thereof by a hollow portion disposed crosswise thereof and extending lengthwise of the crank shaft of the motor, said crosswise-extending portion presenting at its upper side a substantially flat surface, and said last-referred-to portion containing an upwardly opening recess and said extension timer extending into the recess in said tube.

GUSTAF A. SAFSTROM.
